UNITED STATES PATENT OFFICE.

CHARLES H. CALKINS, OF LUDLOW, MASSACHUSETTS, ASSIGNOR TO BAUSH MACHINE TOOL COMPANY, A CORPORATION OF MASSACHUSETTS.

MACHINE FOR GRINDING WORM-THREADS.

1,275,218.

Specification of Letters Patent. Patented Aug. 13, 1918.

Application filed March 17, 1916. Serial No. 84,854.

To all whom it may concern:

Be it known that I, CHARLES H. CALKINS, a citizen of the United States, residing in Ludlow, Massachusetts, have invented certain new and useful Improvements in Machines for Grinding Worm-Threads, of which the following is a specification.

The invention aims to provide a machine for grinding worm threads with an emery or other abrading wheel. The worms of worm gearing are ordinarily made of steel and after being cut to shape are hardened by heat treatment which sometimes distorts the shape of the thread and lessens its efficiency. Such threads, therefore, are ground down to the exact shape desired by means of abrading wheels. The invention provides a machine of great simplicity and accuracy for performing such a grinding operation automatically.

The accompanying drawings illustrate an embodiment of the invention.

Figure 1 is a side elevation of a worm such as the illustrated machine is adapted to grind;

Fig. 2 is a cross-section of the same on the line 2—2, Fig. 1, showing the grinding wheel also in place;

Fig. 3 is a side elevation of the machine with a detail thereof in section;

Figs. 4 and 5 are respectively a plan and an end elevation of the machine.

The worm is formed with end portions A and B of various shapes for various uses and with an intermediate threaded portion, the threads C of which (Fig. 2) are formed with inclined bearing faces D. The grinding operation is performed on these inclined faces D of the spiral threads.

The machine is provided with a beveled abrading wheel E, the beveled faces F of which bear against the beveled faces D of the worm and the worm is fed spirally so that its beveled faces are ground to a true spiral as the wheel rotates against them. The feed mechanism is driven from a belt pulley G, Fig. 4, on a shaft H, Fig. 3, which through beveled gearing J drives a longitudinal shaft K on the end of which is a worm L driving a worm gear M on the shaft N which carries a pinion N' engaging a gear O on a shaft P which carries a pinion Q engaging a gear R rotating on the shaft N and engaging a rack S on the underside of the bed T which slides

on ways U. On the bed T is carried a tail stock V with a pin W engaging the end B of the worm to be ground and permitting rotation of the same. The bed T carries also a head stock X in which is rotatably mounted a shaft Y which is fastened fixedly on the end A of the worm. A master worm Z is fixedly fastened on the shaft Y of the head stock and is carried at its outer ends in bearings on the supplementary head a. The thread b of the master worm is of exactly the same lead as the threads C of the worm which is to be ground. The thread of the master worm is engaged by a stud c with a tooth-shaped end, the stud being carried fixedly in a heavy bracket d which is fastened solidly to the frame e of the machine. A nut f is fixed on the top of the bracket d and the stud c can be screwed into or out of the same by means of a pin g fastened in the top of the stud. The master worm Z may be withdrawn and another worm of different pitch substituted therefor so as to grind other spiral worms; the stud c being adjustable as explained for different master worms.

Now when the bed T is moved forward by the gearing described it carries with it the tail stock V, the worm C, head stock X and supplementary head stock a, and with them the master worm Z. The bracket d and stud c being fixed, cause the master worm Z to rotate as it is advanced, and with the master worm rotates the worm C which is to be ground, thus insuring that the abrading wheel E shall run exactly in the proper lead path.

In previous machines for grinding the faces of worm threads the longitudinal movement has been obtained by various means and the rotary movement has been obtained by a series of gears driven from the gears which effect the longitudinal movement, so as to secure the desired ratio between the longitudinal speed and the rotary speed of the work; and change gears have been used for changing the ratio. Such machines involve a considerable amount of gearing to secure the desired ratio and adjustability of ratio and these gears, besides being complicated, have necessarily involved a certain lost motion which made it difficult to secure perfect accuracy. An advantage of the present machine lies in the mounting of the means for rotating the work directly and fixedly on the work, so

that it is the exact advance of the work itself which determines the rate of rotation and the latter is, therefore, exactly coöordinated with the rate of advance in the axial 5 direction. At the same time the mechanism for securing rotation at the proper rate of speed is the simplest possible, and change of ratio can be effected with the greatest ease.

The abrading wheel *E* is mounted on a 10 spindle *h* which is rotated at a rapid rate by a pulley *j* driven by a sprocket chain *k* from a motor *l* overhead. The driving of the abrading wheel, therefore, is entirely 15 separate and distinct from the driving of the other movable elements of the machine. The motor unit, including the abrading wheel, is mounted on a turn table consisting of plates *m*, *n* embracing a cross head *o* and having a circular portion *p* rotating within a circular 20 opening in the cross head. The central axis of rotation is indicated at *q* in Fig. 2. It passes through the center of the abrading wheel *E*. The latter can, therefore, be turned about this vertical axis so as to fit 25 its beveled edge between worm threads of any angle. The abrading wheel can be easily withdrawn from the end of its spindle and replaced by another with a different bevel to fit it between worm threads having their 30 faces beveled at different angles.

The abrading wheel with its motor can also be adjusted vertically to fit it for grinding worms of different diameters and to permit it to be fed progressively deeper into the 35 work and to be withdrawn from between a pair of finished threads and introduced into engagement with the beveled faces of a new pair of threads. For this purpose the entire cross head *o* is provided with slides *r* 40 engaging guides *s* carried fixedly by the frame of the machine, and the slides *r* are threaded on the upper ends of shafts *t* which at their lower ends carry beveled gears *u* (Fig. 5) engaging pinions *v* on a trans- 45 versely extending shaft *w* which has at one end a gear *x* driven from a gear *y* on a shaft *z* which is driven from a beveled gear *1* at its upper end engaging a similar gear *2* on a shaft *3* on the outer end of which is fixed a 50 hand wheel *4*. The hand wheel is graduated as indicated in Fig. 5 on its edge and rotates in juxtaposition to a fixed disk *5* carrying an index line, the graduations being proportioned to a movement of a thousandth 55 of an inch of vertical movement of the abrading wheel. When a grinding operation begins the wheel is brought down to engage the beveled side faces of the threads. As the grinding progresses the wheel is fed 60 downward step by step until it makes a full engagement with the beveled faces of the worm thread and grinds it truly throughout the depth of such faces.

The abrading wheel *E*, as shown in Fig. 65 5, is arranged so that its diameter through

the point of engagement with the work (its vertical diameter in the case illustrated) is at right angles to the axis of the work. It needs only to be turned about this diameter to adapt it to grind threads of greater or 70 less pitch. Also by reason of such arrangement the feeding of the grinding wheel is in the direction of the radius of the work, and a simple rectilinear adjustment is all that is necessary to feed it farther into the work 75 for successive grinding operations.

It has been proposed heretofore to use a lead screw, of the same pitch as the work, in machines of this general class, that is where a spiral movement of the work is to be secured; the driving mechanism impressing a rotary movement directly, and the lead screw converting this into a spiral. With such apparatus however, change gears cannot be avoided if the machine is to take a considerable variety of work. It is necessary in some cases to rotate the work more rapidly and in other cases to rotate it more slowly for corresponding linear movement. With my improved machine, the driving mechanism acts directly on the reciprocating bed, and the master worm imposes on the work 85 exactly the rotary speed desired.

In Fig. 2 the worm is indicated as having 90 six threads, and the grinding wheel engaging two threads at the same time. Worms are made with from one to six or even more threads and generally in grinding the wheel will engage only one thread at a time, two operations being required for the grinding 100 of the two faces of each thread. After one thread has been ground the worm must be rotated with respect to the master worm *Z*. In the case of a worm having six threads, this must be given one-sixth of a turn in advance of the master worm, before the emery 105 wheel is again moved down into engagement. This adjustment will be repeated six times for the worm having six threads. The adjustment is accomplished by means of a 110 serrated indexing disk *Y'* (Fig. 3) which coöperates with any usual or suitable latch and permits the worm to be advanced any desired fraction ahead of the master worm. After the adjustment is effected, the worm 115 to be ground and the master worm remain fixed to each other until the worm is completed.

What I claim is—

1. A machine for grinding the beveled 120 side faces of worm threads including in combination means for advancing the work axially and a master worm for rotating it, a beveled abrading wheel adapted to be set at the angle of the threads to be ground, 125 with its beveled face engaging the beveled faces of such threads and its diameter through the point of engagement lying at right angles to the axis of the work, and means for feeding such abrading wheel far- 130

ther into the work in a direction normal to the axis thereof as the grinding progresses.

2. A machine for grinding the beveled faces of worm threads including in combination a bed and rotary means acting directly thereon to reciprocate the same, a master worm having the same lead as the work rotatably mounted on said bed, means for rigidly attaching the same to the work, 5 a fixed device engaging the thread of said master worm and causing the same to rotate with the work as the bed is reciprocated and an abrading wheel adapted to simultaneously engage the side faces of the adjacent threads to be ground.

3. A machine for grinding the beveled side faces of worm threads including in combination a reciprocable bed T, a tail stock carried by said bed and adapted to 10 engage one end of the worm to be ground and to permit rotation of the same, a head stock X also carried by said bed, a shaft Y mounted in said head stock and adapted to be fastened fixedly on the opposite end of 15 the worm to be ground, a master worm fixedly fastened on the shaft Y, a fixed device engaging the thread of said master worm and causing the same to be rotated and advanced axially with the work at the same 20 rate as the threads on the work, and an abrading wheel adapted to simultaneously engage the adjacent threads of the work.

4. A machine for grinding the beveled side faces of worm threads including in combination a reciprocable bed T, a tail stock carried by said bed and adapted to 25 engage one end of the worm to be ground and to permit rotation of the same, a head stock X also carried by said bed, a shaft Y mounted in said head stock and adapted to 30

be fastened fixedly on the opposite end of the worm to be ground, a master worm fixedly fastened on the shaft Y, a fixed device engaging the thread of said master worm and causing the same to be rotated and advanced axially with the work at the same 35 rate as the threads on the work, and an abrading wheel adapted to simultaneously engage the adjacent faces of the threads of the work, the means for fastening the shaft 40 Y to the work being adapted to effect an angular adjustment between such parts.

5. A machine for grinding the beveled faces of worm threads including in combination a bed and rotary means acting directly 45 thereon to continuously reciprocate the same, a master worm rotatably mounted on said bed, a fixed device engaging the thread of the master worm, said master worm being rotated solely by the reciprocation of 50 the bed and the coöperation of the said fixed device, and means for rigidly attaching the work to the master worm.

6. A machine for grinding the beveled side faces of worm threads including in 55 combination means for advancing the work axially and a master worm for rotating it, a beveled abrading wheel adapted to be set at the angle of the threads to be ground, with its beveled face engaging the beveled 60 faces of such threads and its diameter through the point of engagement lying at right angles to the axis of the work, a motor for driving said abrading wheel, a rotatable base for supporting said motor and 65 said abrading wheel.

In witness whereof, I have hereunto signed my name.

CHARLES H. CALKINS.
